BUCKET ARRANGEMENTS FOR POWER LOADERS

Ralph L. Beyerstedt, Libertyville, Ill., assignor to The Frank G. Hough Co., a corporation of Illinois

Application September 15, 1954, Serial No. 456,155

6 Claims. (Cl. 214—140)

This invention relates generally to bucket arrangements for power loaders, and more specifically to an improved bucket construction.

Power loaders as generally known in the art comprise either crawler type tractors or four wheel rubber tired tractors provided with a forwardly facing shovel, a boom pivotally mounted between the shovel and the tractor, link means pivotally mounted between the tractor and the shovel, and some type of control means cooperating with the link means for tilting the bucket for such necessary operations of the loader as digging, carrying and dumping. Recent developments in the art have provided linkage and boom means which will permit a rearward tilt or break-out of the bucket to full load retention position at ground level. However, buckets as generally known in the art do not perform efficiently with such developments. Among other things, it is necessary and desirable that the bucket be sufficiently reinforced, that some portion of the bucket act as a fulcrum for the leverage effect achieved with a break-out design, that some portion of the bottom of the bucket act as a skid shoe when the bucket is moved along the ground in the carrying position, and that any hinges or hinge connections at the bottom of the bucket be adequately protected against damage when the bucket is tilted or skidded. Therefore, it is the object of this invention to provide a bucket construction in a power loader which will fulfill all of the stated necessary and desirable requirements for a simple and efficient bucket.

Other objects and the features of the present invention will be apparent upon a perusal of the following specification and drawing of which:

Figure 1 shows a side plan view of a representative loader provided with the novel bucket construction of the invention;

Figure 2 is a rear plan view of the bucket only of the structure shown in Figure 1; and

Figure 3 is a side plan view of the bucket shown in Figure 2.

The present embodiment is the preferred embodiment but it is to be understood that changes can be made in the present embodiment by one skilled in the art without departing from the spirit and scope of this invention.

For a detailed description of the present invention reference is made to the drawing. The loader of the present invention comprises a vehicle 10 of any type well known in the art. A boom 11 is also provided, and is pivotally mounted at one end thereof to the vehicle 10 by means of mounting means 12. The other end of the boom 11 extends forwardly of the vehicle 10. The boom 11 is formed in duplicate portions positioned on each side of the vehicle 10. A hydraulic ram 16 is provided in duplicate portions disposed on each side of the vehicle 10 for raising and lowering of the boom. The head end of the hydraulic ram 16 is pivotally mounted to the vehicle 10 by means of mounting means 17. The rod end of the hydraulic ram 16 is pivotally mounted to

the boom 11 intermediate the ends thereof by means of a bracket 18 and pivotable mounting means 19. Linkage means are also provided in duplicate portions disposed on each side of the vehicle 10 and comprise a hydraulic ram 13 and a link 14. The head end of the hydraulic ram 13 is pivotally mounted to the vehicle 10 by means of mounting means 15. The rod end of the hydraulic ram 13 is rigidly secured to one end of the link 14 which is positioned to extend forwardly of the vehicle 10. Suitable hydraulic fluid conduits, pumps, and control means (not shown) of any type well known in the art are provided for the operation of the hydraulic rams 13 and 16.

To the forward end of the link 14 and the boom 11, the bucket 20 is mounted. The bucket 20 comprises a substantially U-shaped scoop element 21 of a conventional bucket configuration. A pair of side walls 22 are secured one at each end of the U-shaped scoop element 21. The side walls 22 are formed to have a general configuration as shown in the drawings wherein substantial portions of the side walls 22 extend rearwardly of the scoop element 21 so as to form a pair of spaced apart rearwardly extending flanges having protruding curved sections along a line extending through the deepest portion of the scoop element 21 and generally bisecting the scoop element 21. The rearwardly extending flanges are also provided with a flat or straight section which generally lies in a horizontal plane when the bucket 20 is tipped back approximately as shown in Figure 1. The amount of tip back of the bucket 30 as shown in Figure 1 is generally that amount of tip back which has been found in the art to be the optimum degree of tip back for proper carrying of a filled bucket, approximately 35 degrees from the horizontal. It can thus be seen that since the flat or straight section is substantially horizontal when the bucket is tipped back approximately 35 degrees, the lower marginal edge of the side walls 22 are disposed at an angle of approximately 145 degrees to the flat or straight section of the rearwardly extending flanges. The forward marginal edges of each of the side walls 22 are provided with reinforcing members 23, and the lower forward marginal edges of the side walls 22 and the forward marginal edge of the lower leg of the scoop element 21, are provided with a cutting edge 24. The upper portion of the bucket 20 is reinforced by an L-shaped channel member 25 which is secured between the side walls 22 and the rear face of the scoop element 21 substantially at the upper marginal edges thereof. To aid in reinforcing the bucket 20, and to provide some of the means for pivotally mounting the bucket 20 to the boom 11 and the link 14, a pair of flanges 26 are provided. To additionally reinforce the bucket 20 and to provide the remainder of the means for pivotally mounting the end of the link 14 to the bucket 20, a second pair of flanges 27 are provided. The remaining means for pivotally mounting the end of the boom 11 to the bucket 20 are a third pair of flanges 28. The flanges 26, 27 and 28 are secured to the rear face of the scoop 21 of the bucket 20 and are dimensioned to extend from the rearward face of the scoop 21 a distance equal to or less than the distance that the rearwardly extending flange portions of the side walls 22 extend. The forward end of each portion of the link 24 is pivotally mounted between one of the flanges 26 intermediate the ends thereof and one of the flanges 27 substantially at the upper end thereof by means of mounting means 41. The forward end of each portion of the boom 11 is pivotally mounted between the lower end of one of the flanges 26 and the lower end of one of the flanges 28 by means of mounting means 40.

The bucket 20 is also provided with a plate 42, a plate 43, and a pair of plates 44. Plates 42, 43 and 44 are each formed with part of the periphery thereof

shaped substantially identically to the shape of the protruding curved sections and the adjacent straight sections of the side walls 22. The plates 42, 43 and 44 are mounted to the rear face of the scoop element 21 with identically shaped surfaces in registry with the side walls 22, and with plate 42 positioned adjacent one of the flanges 27, plate 43 positioned adjacent the other flange 27, and with pairs of plates 44 positioned between flanges 28. The bucket 20 is further defined by three curved plates 29, 30 and 31. The curved plates 29, 30 and 31 are formed to have a curvature substantially identical to the shape of the protruding curved section of each of the side walls 22 and the substantially straight section adjacent thereto, and the plates 42, 43 and 44. The curved plate 29 is secured to the marginal edges of the protruding curved section and the straight section adjacent thereto of one of the side walls 22 and plate 42. The curved plate 30 is secured to the marginal edges of the pair of plates 44. The curved plate 31 is secured in a similar manner as curved plate 29 to the other side wall 22 and the plate 43. Three rectangular plates 32, 33 and 34 are also provided. The plate 32 is secured to the upper marginal edges of the curved plate 29, the plate 42, and to the rear face of the scoop 21 and one of the side walls 22. Plate 33 is secured to the upper marginal edges of the curved plate 30, the pair of plates 44, and to the rear face of the scoop 21. Plate 34 is secured to the upper marginal edges of the curved plate 31, the plate 43, and to the rear face of the scoop 21 and the other side wall 22. In order to provide bearing and wearing surfaces for the curved plates 29, 30 and 31, three skid shoes 35, 36 and 37 are provided. The skid shoes 35, 36 and 37 are curved to have substantially the same curvature as the surfaces of the plates 29, 30 and 31 and are secured to the surfaces of these plates respectively. The skid shoes 35, 36 and 37 may be removably secured to the plates 29, 30 and 31 in order that they may be replaced when worn.

Turning next to a description of the operation of the instant invention, the bucket 20 may be positioned as shown in Figure 3 by an extension of the hydraulic ram 13. This is the well known dig position, and when the vehicle 10 is moved forwardly, the cutting edge 24 will bite into the material to be dug to fill the bucket 20. It should be noted that during this operation, the bucket 20 is resting on the ground. If the hydraulic ram 13 is then retracted, the loaded bucket 20 will pivot in a counterclockwise direction as viewed in Figure 1 about pivotal mounting means 40. It can thus be seen that the skid shoes 35, 36 and 37 will act as wide fulcrums, transversely of the bucket 20, for the tilting of the bucket 20. The load of the bucket will not be transferred to the boom 11, but will be transferred to the ground over the width of the skid shoes 35, 36 and 37. When the hydraulic ram 13 is stopped at the point wherein the bucket will assume the position shown in Figure 1, the full load retention position, the skid shoes 35, 36 and 37 will distribute the load of the bucket over a wide area to support the bucket on any relatively soft material over which the vehicle 10 is moved. With a substantial amount of the weight of the bucket removed from the boom 11 and the linkage means, a relatively heavy load may be moved over the ground.

As is known in the art, oftentimes in the operation of a conventional loader, the cutting edge when disposed within a heavy material, will not, due to the excessively large moment of force, permit an immediate tip back of the bucket. However, it has been found that with the fulcruming effect of the present invention, a conventional loader provided with bucket 20 may be easily tipped back or pried out of the heavy material.

Since the pivotal mounting means 40 and 41, and the flanges 26, 27, and 28, for mounting of the boom 11 and the link 14 to the bucket 20 are projected, a locked-

up condition wherein the flanges and pivotal mounting means are projected into the ground, is avoided.

Further, the reinforcing effect of the various described elements of the subject bucket, is substantial, and twisting and distorting of the bucket is held to a minimum.

Although the present embodiment discloses a construction providing three separate skid shoe sections, different bucket usages may permit, or different loader constructions may necessitate, a change in the number of skid shoe sections required. If the boom and link connections are substantially at the outer edges of the bucket, one center skid shoe section may suffice. If the boom and link connections are substantially at the center of the bucket, the outer pair of skid shoe sections may suffice.

Having described the invention what is considered new and desired to be protected by Letters Patent is:

1. In a loader, a bucket comprising a scoop element, boom and linkage pivotal mounting means formed on the rear face of said scoop element, a skid shoe section mounted on the rear face of said scoop element and formed to project rearwardly of said boom and linkage pivotal mounting means, said skid shoe section formed to provide a fulcrum line at ground level when said bucket is pivoted about said boom pivotal mounting means, said skid shoe section further formed to provide a relatively flat surface for the skidding of said bucket when said bucket is pivoted to a full load retention position at ground level.

2. In a loader, a bucket comprising a scoop element, boom and linkage pivotal mounting means formed on the rear face of said scoop element, a plurality of skid shoe sections mounted on the rear face of said scoop element, each of said plurality of skid shoe sections comprising a pair of spaced apart rearwardly projecting flange portions, a plurality of curved plates, each of said curved plates secured to one of said pair of flange portions, a plurality of curved skid shoes, each of said curved skid shoes secured to the surface of one of said curved plates, each of said pair of rearwardly extending projecting flange portions formed to position each of said skid shoes rearwardly of said boom and linkage pivotal mounting means, said curved plates and said skid shoes having curvatures providing a fulcrum line at ground level when said bucket is pivoted about said boom pivotal mounting means and a relatively flat surface for the skidding of said bucket when said bucket is pivoted to a full load retention position at ground level.

3. In a loader, a bucket comprising a U-shaped scoop element, a pair of side walls secured to said U-shaped scoop element and formed to extend rearwardly of said scoop element, boom and linkage pivotal mounting means formed on the rear face of said scoop element, a pair of skid shoe sections mounted on the rear face of said scoop element and including the portions of each of said side walls formed to extend rearwardly of said scoop element, said pair of skid shoe sections formed to project rearwardly of said boom and linkage pivotal mounting means, said pair of skid shoe sections further formed to provide a fulcrum line at ground level when said bucket is pivoted about said boom pivotal mounting means, said pair of skid shoe sections further formed to provide a relatively flat surface for the skidding of said bucket when said bucket is pivoted to full load retention position at ground level.

4. In a loader, a bucket comprising a substantially U-shaped scoop element having a pair of side walls secured thereto, each of said pair of side walls having a portion extending rearwardly of said scoop element, each of said portions formed to have a straight section disposed at an angle to the lower marginal edge of said bucket, a plurality of flanges secured to the rear face of said scoop element in a spaced apart relationship to each other and said portions of said side walls, each of said

flanges having straight sections in registry with said straight sections of said portions of said side walls, a plurality of curved plates secured to the outer marginal edges of said flanges and said portions of said side walls, a plurality of skid shoes mounted to the surfaces of said plates, boom and linkage pivotal mounting means formed on the rear face of said scoop element between said plates, said plurality of flanges and said portions of said side walls formed to project said curved skid shoes rearwardly of said boom and linkage pivotal mounting means, said plurality of plates and said skid shoes formed to provide a fulcrum line at ground level between said lower marginal edge of said bucket and said straight sections when said bucket is pivoted about said boom pivotal mounting means, the portions of said plurality of curved plates and said skid shoes adjacent said straight sections formed to provide a relatively flat surface for skidding of said bucket when said bucket is pivoted to a full load retention position at ground level.

5. In a loader, a boom, linkage means, said boom and linkage means pivotally mountable at one end thereof on said loader, the other ends of said boom and linkage means projecting forwardly of said loader, a bucket comprising a scoop element, boom and linkage pivotal mounting means formed on the rear face of said scoop element, means pivotally mounting said other ends of said boom and linkage means to said boom and linkage pivotal mounting means, said linkage means operable to pivot said bucket rearwardly at ground level to a full load retention position, a skid shoe section mounted on the rear face of said scoop element and formed to project rearwardly of said boom and linkage pivotal mounting means, said skid shoe section formed to provide a fulcrum line at ground level when said bucket is pivoted rearwardly about said boom pivotal mounting means, said skid shoe section further formed to provide a relatively flat surface for the skidding of said bucket when said bucket is pivoted to a full load retention at ground level.

6. In a loader, a boom, linkage means, said boom and linkage means pivotally mountable at one end thereof on said loader, the other ends of said boom and linkage

means projecting forwardly of said loader, a bucket comprising a substantially U-shaped scoop element having a pair of side walls secured thereto, each of said pair of side walls having a portion extending rearwardly of said scoop element, each of said portions formed to have a straight section disposed at an angle to the lower marginal edge of said bucket, a plurality of flanges secured to the rear face of said scoop element in a spaced apart relationship to each other and said portions of said side walls, each of said flanges having straight sections in registry with said straight sections of said portions of said side walls, a plurality of curved plates secured to the outer marginal edges of said flanges and said portions of said side walls, a plurality of skid shoes mounted to the surfaces of said plates, boom and linkage pivotal mounting means formed on the rear face of said scoop element between said plates, means pivotally mounting said other ends of said boom and linkage pivotal mounting means, said linkage means operable to pivot said bucket rearwardly at ground level to a full load retention position, said plurality of flanges and said portions of said side walls formed to project said curved skid shoes rearwardly of said boom and linkage pivotal mounting means, said plurality of plates and said skid shoes formed to provide a fulcrum line at ground level between said lower marginal edge of said bucket and said straight sections when said bucket is pivoted about said boom pivotal mounting means, the portions of said plurality of curved plates and said skid shoes adjacent said straight sections formed to provide a relatively flat surface for skidding of said bucket when said bucket is pivoted to a full load retention position at ground level.
